(73) Assignee: **Bridgestone Corporation**, Tokyo (JP)

(74) Attorney, Agent, or Firm — Sughrue Mion, PLLC

(**) Term: **14 Years**

(57) **CLAIM**

(21) Appl. No.: **29/447,871**

The ornamental design for a tread portion of an automobile tire, as shown and described.

(22) Filed: **Mar. 7, 2013**

DESCRIPTION

(30) **Foreign Application Priority Data**

Oct. 19, 2012 (JP) 2012-025503
Oct. 19, 2012 (JP) 2012-025504

(51) **LOC (10) Cl.** **12-15**

FIG. 1 is a perspective view of a tread portion of an automobile tire according to a first embodiment of our new design;

(52) **U.S. Cl.**

FIG. 2 is a front view thereof;

USPC **D12/550**

FIG. 3 is a top view thereof;

(58) **Field of Classification Search**

FIG. 4 is a right side view thereof;

USPC D12/533-567, 582, 584-585, 900-901;
152/209.1-209.9, 209.11-209.19,
152/209.21-209.28, 455

FIG. 5 is a left side view thereof;

See application file for complete search history.

FIG. 6 is a rear view thereof;

(56) **References Cited**

FIG. 7 is a fragmentary enlarged view showing the details of the tread portion thereof;

U.S. PATENT DOCUMENTS

FIG. 8 is an end view taken along line **8-8** in FIG. 7;

D380,994 S * 7/1997 Morishita et al. D12/550
D450,032 S * 11/2001 Heinen D12/550
D464,311 S * 10/2002 Graas D12/550
